TRAFFIC SIGNAL LIGHT

Frank M. D'Addabbo, New Britain, Conn.
Application April 17, 1956, Serial No. 41,114

Term of patent 7 years
(Cl. D72—1)

FIG. 2.

FIG. 1.

FIG. 4.

FIG. 3.

Fig. 1 is a front view of a traffic signal light showing my new design;

Fig. 2 is a side elevational view thereof;

Fig. 3 is a top plan view of the traffic signal light; and
Fig. 4 is a rear view thereof.

I claim:

The ornamental design for a traffic signal light, as shown.
